MIXING, KNEADING, SHREDDING, PULPING,
AND LIKE MACHINEJohn Edward Pointon, Peterborough, England,
assignor to Baker Perkins Limited, Peter-
borough, England.Application February 7, 1944, Serial No. 521,469
In Great Britain January 28, 1943

3 Claims. (Cl. 259—129)

This invention relates to machines for mixing, kneading, shredding, pulping or the like, of the type wherein a pair of bladed elements is mounted to rotate on parallel axes in a casing comprising a pair of arcuate troughs separated by a saddle piece or co-operative edge, each element being provided with blades extending continuously across the transverse medial plane (which may be conveniently referred to hereinafter as the middle plane) of the element or trough and towards the ends of the trough.

An aim of the present invention is to provide an improved bladed element such that the operative blade length of the element is increased with a view to affording a greater output as compared with that of known machines, without increasing or significantly increasing the amount of power required for the operation of the machine.

A further object of the present invention is to increase the smoothness of action of the machine so that a better balance is effected and local fluctuations in loading are avoided.

The invention consists in a bladed element having a plurality of blades arranged in pairs which are shaped and adapted alternately to disperse and collect or condense the material treated respectively towards the ends of the trough and towards the middle plane thereof. Each of the dispersing pair of blades is preferably continuous over the middle plane and has clearances at its ends with respect to the ends of the trough while the other pair of blades is continuous from the ends of the trough but interrupted to provide a clearance towards the said middle plane to provide in each case for the disposal or passage of axially displaced material.

In the preferred form each bladed element has a plurality of blades arranged in two pairs each member of one pair comprising a continuous blade terminating short of the ends of the trough and having portions of opposite inclination or helical pitch, while each member of the other pair comprises blades also having portions of opposite inclination or pitch but disposed in the reverse sense to that of the first mentioned pair and having an interruption towards the middle plane of the trough.

The invention also consists in a machine for mixing, kneading, shredding or pulping, having a pair of arcuate troughs separated by a saddle piece, each trough accommodating a bladed element having the features set out in the preceding three paragraphs.

In the accompanying drawings:

Figure 1 is a perspective view of a bladed ele- 55

Figure 2 is an end elevation of the element, and

Figure 3 is a diagrammatic plan view of a mix- 5 ing or like machine with the improved bladed element in position.

In carrying the invention into effect according to one mode a machine is provided having a pair of arcuate troughs 1, 2 separated by a saddle piece 3 according to known construction and each having axially arranged bearings 4 for one of a pair of bladed elements 5, 6. The bladed elements according to one form of the invention as described by way of example, comprise trunnion members 7 adapted to be accommodated in the bearings 4 referred to, the inner ends of the trunnions having bosses 8 upon which the blades of the elements are mounted. The blades are of bar form to afford clearances towards the axes of the troughs for the movement of the material under treatment. Each of one pair of blades 9 with which the elements are provided is mounted upon or is integral with a projecting lug or piece 10 extending axially and radially from the inner end of each of the trunnion bosses 8. Each of 15 these blades 9 is continuous between the two supporting lugs 10 and is bent or articulated at 11 in the region of the middle plane. Thus each half or portion of the blade on the opposite sides of the middle plane is inclined or is of helical form 20 of opposite hand. As viewed in plane each blade 9 is similar to that of a wide open V, the arrangement being such that in the rotational sense the pointed end or angle 11 of the V leads and consequently the material dealt with by the helical 25 sides of the blade is dispersed axially away from the middle plane. The disposition of the lug mounting 10 referred to above affords a clearance between the ends of this pair of blades and the ends 12 of the trough so that the material axially 30 displaced by the V shape of the blades can pass out of the path of said blades through the clearances or passages afforded at their ends.

The other pair of blades 13 is mounted on radial ribs or projections 14 extending from 35 the cylindrical surface of the bosses 8. In this case each of the pair constitutes in effect two blades or such may be viewed as a single blade interrupted in the region of the middle plane. For example, each blade portion extends from the 40 boss towards the middle plane and as it approaches said plane it is bent or turned inwardly to form a supporting or uniting cross member 15 with a similar blade portion upon the opposite side of the axis of the pair.

The blade portions of the blades 13 on one side 55 of the middle plane are of similar helical or

inclined form or shape but are of opposite hand or inclination. The cross-piece 15 unites the interrupted portions of the blades and affords a supporting structure in the form of an X, the legs of which afford a passage or clearance adjacent the middle plane so that the material displaced or condensed towards the said planes escapes through said clearance out of the path of these blades. The portions of the blades 13 are of opposite inclination to the corresponding portions of the blades 9.

As the two pairs of blades 9 and 13 are oppositely disposed it will be appreciated that the material operated upon in the troughs 1 and 2 is given an axial displacement alternately towards and away from the middle plane.

By the arrangement of the clearances at the ends of the bladed elements and at the middle plane and with the opposite or reversed inclination of the blades, the material diverted or dispersed away from the middle plane by the blades 9 will pass through the end clearances and be caught up by the next following blade 13 and brought towards the middle clearance, which in turn will allow the material to pass through to be operated upon by the advancing point of the following V-shaped blade portion 9.

Although it is preferred to support one pair of bar form blades at the ends and the other pair at the ends and connected at the middle, the blades may be of plate form having interstices and apertures to allow more or less free passage of the material under treatment.

The pitch of the helical form of the blades may embrace 180° between the trunnions, or if more than four blades are employed a correspondingly lesser pitch may be adopted.

The edges of the blades 9 and 13 may be serrated as shown or serrated plates may be secured to the blades in any convenient manner. The saddle piece 3 may be similarly serrated.

I claim:

1. A bladed element adapted for rotation with-

in the trough of a mixing, kneading, shredding or pulping machine, comprising axially spaced trunnions, bosses on the inner ends of the trunnion, two pairs of blades integral with said bosses, said plates adapted to cooperate with a fixed saddle piece located in said trough, the blades of one pair being continuous and terminating short of the ends of the trough and having portions of opposite inclination so as to form a substantial V, the blades of the other pair having portions of opposite inclination but disposed in the reverse sense to the first pair and extending to the ends of the trough but interrupted adjacent the middle plane of the trough and an integral piece of X-shape formation arranged substantially parallel to the axis of the blades connecting the adjacent ends of the interrupted blades together.

2. A bladed element as claimed in claim 1, wherein the blades are helically inclined and are provided with serrated edges.

3. A machine for mixing, kneading, shredding or pulping, comprising a pair of intersecting arcuate troughs, a saddle piece located at the intersection of said troughs, a bladed element located in each trough for rotation therein, each element comprising axially spaced trunnions, bosses on the inner ends of the trunnions, two pairs of blades integral with said bosses, said blades adapted to cooperate with said saddle piece, the blades of one pair being continuous and terminating short of the ends of the trough and having portions of opposite inclination forming a substantial V, the blades of the other pair having portions of opposite inclination but disposed in a reverse sense to the first pair and extending to the ends of the trough but interrupted adjacent the middle plane of the trough and an integral piece of X-shape arranged in a plane parallel to the axis of the blades and connecting the adjacent ends of the interrupted portions of the blades together.

JOHN EDWARD POINTON.
